PACKAGING DEVICE AND CAP-STOPPER
CLOSURE

Nicholas T. Baldanza, Rutherford, N. J., assignor,
by mesne assignments, to Columbia Protekto-
site Co., Inc., Carlstadt, N. J., a corporation of
Delaware.

Application July 19, 1950, Serial No. 174,745

3 Claims. (Cl. 220—35)

1

This invention relates to packaging devices or receptacles with closures for use in attractively marketing products and providing a handy container for storing the product to make the same repeatedly available for use. More particularly the invention is directed to an improvement in container having a readily removable closure of novel construction and to such closures and new articles of manufacture for use as cap-stopper closures.

Among the objects of the invention is to generally improve devices of the character described which shall comprise few and simple parts that are readily assembled to form attractive packaging receptacles that can serve as a container to permit repeated removal and replacement of the contents or to form cap-stopper closures of novel construction, which shall be cheap to manufacture and capable of being made in quantity production, which shall be easy to keep in a clean sanitary and hygienic condition when employed as a container for repeated use, and which shall be practical and efficient to a high degree.

Other objects of the invention will in part be obvious and in part hereinafter pointed out.

The invention accordingly consists of features of construction, combination of elements and arrangement of parts which will be exemplified in the construction hereinafter disclosed, the scope of the application of which will be indicated in the claims following.

In the accompanying drawing in which one embodiment of the invention is shown,

Fig. 1 is a front elevational view of a packaging device constructed to embody the invention in the form of an improved receptacle having a novel closure construction suitable for marketing toothbrushes and the like in an attractive form and providing a handy container or holder for the toothbrush with a handy removable closure for repeated use shown in closed position and partly broken away to expose the contents.

Fig. 2 is an enlarged top plan view of the improved device shown in Fig. 1.

Fig. 3 is an enlarged fragmentary cross-sectional view taken on line 3—3 in Fig. 2 showing details of the improved cap-stopper closure.

Fig. 4 is a fragmentary cross-sectional view of the container capped portion corresponding to a section taken on line 4—4 in Fig. 3.

Fig. 5 is an enlarged fragmentary view similar to Fig. 3 showing the improved cap-stopper in an open position, and

Fig. 6 is an enlarged plan view of the device as seen from line 6—6 in Fig. 5.

2

Referring in detail to the drawing 10 denotes a packaging device or receptacle adapted to be used for attractively marketing a product, and also providing a handy container for making repeatedly available the contents, as here shown, the product being a toothbrush B, said packaging device and a cap-stopper closure 11 thereof being constructed to embody the invention.

As seen from Fig. 1, device 10, may comprise 10 a container 12 which for the purpose of marketing a contained article, such as toothbrush B, may be made of clear transparent, colored translucent or colored opaque tubular body 12a closed at one end 12b and open at the other end 12c. 15 The latter may be provided with an exterior extended rim edge bead 12d, said container 12 being shaped and sized to conform to the dimensions of the contents, here shown to accommodate toothbrush B. As shown in Fig. 6 said container 12 may be of oval-like sectional shape to permit the toothbrush B to be freely inserted and removed from the container 12 yet neatly fitted therein as indicated in Fig. 1. Container 12 may be, if desired, molded of a suitable plastic material having so-called "shatterproof" properties.

Toothbrush B is confined in said container 12 by cap-stopper closure 11 of improved construction and may be made of a molded resilient material, for example, rubber or a suitable plastic, such as polyethylene.

Cap-stopper closure 11 when molded may be initially formed as a single piece stretched out structure corresponding to that shown in Figs. 5 and 6, and is seen to comprise an expandable annular band portion 11a having a resilient clamping flange 11b sized and shaped to seat and grip the exterior surface of container open end 12c under, that is, inwardly of said bead 12d. And spaced from said band portion 11a but joining therewith through an integrally formed foldable hinge interconnection 11c there is provided a capping portion 11d of a size and shape to extend over the container open end 12c as shown in Figs. 1 to 4.

Said capping portion 11d, as here shown, has a contour substantially like annular band portion 11a but having a somewhat larger spread to provide an encircling peripheral sealing edge border 11e. An integral collar or ring 11f may be provided to outstand from depressed surface 11g of said capping portion 11d and convex surface 11h of said capping portion 11d opposite said surface 11g may have projecting therefrom spaced apart reinforcing ribs 11i which extend thereacross from said hinge interconnection 11c to an integral finger engaging lip 11j terminating the

free end of capping portion 11d. One or more spaced depressions 11k may be provided in capping portion 11d as for example, in the mid section thereof between reinforcing ribs 11h, thin walls 11m of said depression 11k being puncturable to form through-passage for communicating the interior of container 12 with the surrounding atmosphere, as is clear from Figs. 3 to 5.

For further stiffening capping portion 11d additional reinforcing means such as rib 11n spaced from and extending in the same direction as said rib 11h may be provided if desired to brace said capping portion 11d against bending stress and strains when finger pressure is applied to lip 11j on opening or on closing said capping portion 11d from a seated position shown in Fig. 3 in the manner hereinafter described.

After constructing or providing a suitable container 12, and a cap-stopper closure 11 as above described and shown in Figs. 1 to 6, the utility of the invention for use as a packaging device 10 of the character described will be apparent.

Container 12 may be fitted with said annular band portion flange 11a so that the latter is clampingly seated on exterior surface of container 12 against rim bead 12d, as shown in Fig. 5, in which position capping portion 11d is in normally molded stretched out open position. The contents, namely, toothbrush B can then be readily inserted in the container 12 and by finger gripping lip 11j, capping portion 11d may be folded over container open end 12c by bending hinge interconnection 11e transversely the length thereof at bight 11p, as shown in Figs. 1 and 3, and rim edge border of collar 11e forced in a releasably capping position against the interior surface at said container open end 12c, said collar 11e being shaped and sized to snugly seat in said open end 12c and said edge border 11s forming a peripheral sealing joint as shown in Figs. 1 to 3.

Packaging device 10 when sealed closed may be readily opened by simply grasping container 12 in hand and exerting a lifting force with respect thereto on finger engaging lip 11j. Once the sealing joint formed by edge border 11s is broken and the collar 11e unseated from container open end 12c sealing portion 11d will spring into stretched open position shown in Fig. 5.

If it is desired to ventilate the interior of container 12 of package device 10 fitted with cap-stopper closure 11 in effective position, thin wall depression 11m may be pierced or cut to provide through-passage communicating with the atmosphere as is clear from Figs. 1 to 4.

It will thus be seen that there is provided a packaging device and cap-stopper closure of the character described whereby the several objects of this invention are achieved and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

Having thus described my invention, I claim as new and desire to secure by Letters Patent:

1. A cap-stopper closure of the character described for an open ended container comprising a one-piece resilient structure having an annular band portion adapted to be fitted to an exterior rim border of said container open end, a

capping portion formed with an integral collar outstanding from a depressed surface of said capping portion adapted to seal against the interior wall of said container, a hinge interconnection joining said band portion to the capping portion, a finger gripping lip terminating to extend from said capping portion in alignment with and opposite said interconnection, said capping portion being so constructed and arranged to fold over at said hinge interconnection from an open position on application of a bending pressure on said lip to a position superimposing the capping portion collar over said annular band portion to form a closure for the container open end, said capping portion being of greater area than said container open end forming an encircling peripheral sealing edge border extending beyond said collar, a convex surface formed on said capping portion opposite said depressed surface, and spaced apart reinforcing ribs outstanding to extend along said convex surface from the lip to said hinge interconnection, a mid region of the capping portion between said ribs having a puncturable wall of reduced thickness to form a permanent through passage when pierced.

2. A packaging device of the character described comprising an elongated container of substantially uniform cross section having an open end through which the contents are inserted, an exterior bead formed at said container open end, a one-piece resilient cap-stopper closure having an annular band portion shaped and sized to snugly fit said container cross section abutting said exterior bead, a capping portion of said cap-stopper formed with an integral collar for clampingly seating in an effective closed position against the interior wall of said container, a hinge interconnection integrally joining said band portion with the capping portion, a finger gripping lip terminating said capping portion extending in an alignment with and opposite said interconnection for seating and unseating said capping portion from said effective closure position and spaced apart reinforcing ribs outstanding from a surface of said capping portion extending from the lip to said hinge interconnection, said capping portion having a contour of greater area than said container open end forming an encircling peripheral edge border sealing closure extending beyond said collar for said beaded container open end.

3. The packaging device defined in claim 2 in which said capping portion is formed with a mid-region depression between said ribs having a weakened puncturable wall of reduced thickness for forming when pierced a permanent through-passage communicating the interior of said container with the atmosphere when said capping portion is in said closed position.

NICHOLAS T. BALDANZA.
